GIRDLE

Paul E. Ambrose, Dover, Del., assignor to International
Latex Corporation, Dover, Del., a corporation of Dela-
ware

Application September 13, 1955, Serial No. 37,896

Term of patent 14 years

(Cl. D20—2)

Fig. 1.

Fig. 2.

Figure 1 is a front view; and
Figure 2 is a rear view of a girdle showing my new
design.

The characteristic features of my new design reside in
the specific perforated pattern on the front and rear
faces of the girdle, said pattern terminating in a plurality
of shallow points at the top thereof and having sinuous
effects on both sides and the bottom of each pattern as
shown.

I claim:

The ornamental design for a girdle, substantially as
shown and described.
